US00D769989S

(12) **United States Design Patent** (10) Patent No.: **US D769,989 S**
(45) Date of Patent: **** Oct. 25, 2016**

(54) **CONVERGENT TREADMILL DESK**

(71) Applicant: **Brunswick Corporation**, Lake Forest, IL (US)

(72) Inventors: **Paul Brian Siebert**, Chicago, IL (US); **William Cesare Cesaroni**, Glenview, IL (US); **Morad Ghassemian**, Oak Park, IL (US); **Brian Young Lee**, Glenview, IL (US); **Christopher Justin Mayer**, Chicago, IL (US)

(73) Assignee: **Brunswick Corporation**, Lake Forest, IL (US)

(**) Term: **15 Years**

(21) Appl. No.: **29/531,676**

(22) Filed: **Jun. 29, 2015**

(51) LOC (10) Cl. **21-02**

(52) U.S. Cl.

USPC **D21/669**

Assistant Examiner — Ryan Harvey

(74) Attorney, Agent, or Firm — Andrus Intellectual Property Law, LLP

(57) **CLAIM**

The ornamental design for a convergent treadmill desk, as shown and described.

DESCRIPTION

FIG. 1 is a front perspective view of the convergent treadmill desk showing our new design;

FIG. 2 is a left side elevation view thereof;

FIG. 3 is a right side elevation view thereof;

FIG. 4 is a back side elevation view thereof;

FIG. 5 is a front side elevation view thereof;

FIG. 6 is a top plan view thereof; and,

FIG. 7 is a bottom plane view thereof.

The broken lines in the figures show portions of the convergent treadmill desk that form no portion of the claimed design.

1 Claim, 7 Drawing Sheets
